UNITED STATES PATENT OFFICE.

CHARLES F. SCOTT, OF PITTSBURGH, PENNSYLVANIA, ASSIGNOR TO WESTINGHOUSE
LAMP COMPANY, A CORPORATION OF PENNSYLVANIA.

MOUNTING TUNGSTEN FILAMENTS.

1,013,227.

Specification of Letters Patent.

Patented Jan. 2, 1912.

Application filed December 22, 1908. Serial No. 468,706.

To all whom it may concern:

Be it known that I, CHARLES F. SCOTT, a citizen of the United States, and resident of Pittsburgh, county of Allegheny, State of Pennsylvania, have invented certain new and useful Improvements in Mounting Tungsten Filaments, of which the following is a specification.

My invention relates to a method of and means for supporting filaments for incandescent electric lamps and is particularly applicable to fragile filaments such, for instance, as those made of tungsten, tantalum, molybdenum, etc., although many features of my invention are applicable to filaments of other material. Heretofore it has been customary to rigidly cement or fuse the ends of the filaments into metallic leading-in or supporting wires and to provide anchors for the loops of the filaments. In the case of tungsten filaments, flexible or yielding supports have been used for the supporting wires as well as for the anchors, and various other means have been proposed for guarding against sudden jars and stresses being placed upon the filaments and which are liable to break them.

My invention contemplates mounting the filaments loosely in their supports instead of rigidly fastening them to their supports. The current carrying contact is therefore a mechanical contact, the surfaces usually being held in contact by tension upon the filament.

In its simplest form a straight filament may have its two ends bent into hooks which are hooked over terminals through which current passes. Filaments of other shapes, such as of hair pin shape, may have the two ends bent into hooks which pass loosely through loops or hooks in the leading-in or supporting wires; in this case the bend of the filament midway between its ends will preferably be supported by a suitable anchor wire which exerts a tension upon the filament thereby holding the hooked connections at the ends firmly in place. In ordinary practice it is customary to rigidly fasten the end of the filament to its supporting wire.

The connection is sometimes made by a ce-

ment or paste and sometimes by fusing a metal supporting wire around the end of the filament. In the manufacture of tungsten lamps, for example, a method in common practice is to surround the end of the filament by a small hook at the end of a supporting wire. This hook is then subjected to an electric spark or arc which melts the supporting wire causing it to form in a globule or ball around the tungsten filament. This method of fastening the filaments is objectionable for several reasons. It is a delicate operation and cannot be conducted in the air, but, in order to prevent oxidation of the filament, must be conducted in a neutral gas; the arc is liable to heat and damage the filament. Moreover when the lamp is completed the filament is held rigidly at one end, which in the case, for example, of a tungsten filament, is quite unsatisfactory, as it renders a filament which is inherently fragile all the more likely to be broken, as a blow or shock brings a maximum stress at the point of rigid support. It is well known that filaments in commercial lamps are most likely to break near the point of rigid support. In order to remove these difficulties in the manufacture of the rigidly supported filament, and to avoid these characteristics in the completed lamp, I have devised a method of mechanical connection. This construction is comparatively simple, and the filament, as it is not rigidly held, is permitted a degree of freedom which obviates the liability to breakage by shock which is found in the rigidly supported filament.

In carrying out my invention, various forms of construction may be applied. A filament, whether it takes the form of a straight wire or of a hair pin, may have its two ends bent backward in the form of a hook, and this hook may pass over the supporting wire or through a hook, bend, or loop in the supporting wire, or the hook in the filament may pass through a loose link, which is, in turn, mechanically held by the supporting wire. In some cases I find it advantageous to form a helical coil in the leading-in or supporting wire or in the loose link and pass the bent end of the

hook through this coil, so as to remove the opportunity for the hook to straighten out when heated. In other cases I find it advantageous to form an eye in the end of the filament by taking the end of the hook and bending it around the filament, so as to prevent the hook from straightening out. When this construction is used it is desirable to have the support or link to which the filament attaches of such form that it may readily pass through the eye in the end of the filament. This form reduces the temperature at the point of contact between the filament and its support as it offers two paths for the current to flow. The current in passing from the support divides and flows through the two sides of the eye at the end of the filament, uniting again at the point of contact between the end and the straight part of the filament.

When several filaments are to be supported in a single lamp and connected in series, the several filaments may be hooked to common supports at the points where they are to be electrically connected in series, so that current may pass from one to the other. If the construction of the lamp be such that no external support is required at the junction of two filaments, they may be hooked together directly.

The method of mechanically attaching filaments to their supports lends itself to forms of construction which would be difficult to carry out with the use of a fused contact. Several forms of special construction are shown in the figures.

In the drawings; Figure 1 illustrates a filament, for instance, made from tungsten and adapted to be utilized according to my invention. Fig. 2 shows two such filaments mounted upon an arbor. Figs. 3, 4, 5, 6, 7, 8, 9, 10, 11 and 11^a, illustrate various different adaptations and modifications.

Referring to Fig. 1, 1 represents a filament of hairpin shape having its ends bent into hooks 2, 2. These hooks may be formed by first sufficiently heating the metal, for instance, as tungsten, or if made of other material the hooks may be formed thereon when the filament is made.

In Fig. 2 I have shown a stem, 3, of an incandescent lamp carrying an arbor, 4, which in turn carries two supporting hooks or anchors, 5, 5. The supporting anchors 5, 5, may be made of nickel or other suitable material. The stem 3 carries leading-in wires, 6, 6, which after passing through the stem extend outward laterally and have helical coils 7, 7, at their ends. An additional supporting wire, 8, is also shown, it having no electrical connection. It also carries at its opposite end a similar coil 9. The hooks 2 of the filaments are passed upwardly through the several spirals, two of

them being passed through the same spiral 65 9 upon the supporting wire 8. The helical coils obviate any tendency which might otherwise exist on the part of the hooks to straighten out and release themselves from the leading-in or supporting wires. The 70 loops of the filaments pass through hooks or rings 10, which, in case the filaments are of tungsten, are with advantage also made of tungsten and usually of somewhat larger cross-section than that of the filaments. 75 The hooks or rings 10 are carried by hooks upon the ends of the anchors 5. The anchor wires may be made small and exert a slight tension upon the filaments. The entire structure when thus prepared is inserted 80 into the lamp bulb in the usual manner.

In Fig. 3, a completed lamp is shown containing four filaments in which the loops of the filaments pass through tungsten rings 10 and the hooked ends also extend through 85 rings, 11, of tungsten or other suitable material. The rings, 11, are in turn carried by the hooks, 12, upon the ends of the leading-in and supporting wires. Inasmuch as there might be a tendency, however, for the 90 hooks as shown in Fig. 3, to straighten out, it is sometimes preferable, although not always essential to adopt the structure shown in Fig. 4, in which the rings are replaced by hooks or rings having helical coils 8^a for 95 receiving the hooks of the filament.

In Fig. 5 I have shown a slightly different form of hook at the looped end of the filament from that shown in Fig. 3. The loops or rings are usually of larger 100 cross-section than the filaments themselves and as they do not convey the current they do not become sufficiently heated to straighten out. The looped ends of the filaments are there shown as being spread apart considerably beyond the dimensions of the opening through which the filaments are passed into the base of the lamp. In order to place the mounted filaments of this structure within the bulb, the rings or hooks 110 which support the looped ends of the filaments are moved over their supporting spring wires to a point near the central glass arbor. The spring wires are then bent 115 upward parallel with the arbor and the whole structure is put into the bulb. By working through the small hole at the top end of the lamp prior to its being exhausted, the spring supporting wires are bent into 120 their proper positions and the hooks or rings which carry the looped ends of the filaments are passed out to the ends of the supporting wires and are held in hooks at the ends of these wires.

In Fig. 6, a modification is shown in 125 which an open eye or loop is formed at each end of the filament to receive the supporting wire. This eye is formed by twisting

the filament about itself so as to prevent it from opening under the influence of heat.

In Fig. 7, a form is shown in which two filaments are spread apart in a manner similar to that shown in Fig. 5, the hooked ends of the filaments being held in loose rings which may be of nickel or other suitable material. In this instance the spread of the filaments is such as to afford a good "end on" light.

In Fig. 8, a somewhat similar construction is shown except that the filaments are not spread apart as in Fig. 7, and the filaments are mounted in practically the same manner as shown in Fig. 2.

Fig. 9, shows a lamp with a single filament in which the ends are hooked into helical coils formed in the copper leading-in wires. The ends of these leading-in wires project a sufficient distance beyond the coils to afford additional paths for conducting away and radiating the heat. The looped end of the filament is held in a tungsten or other suitable hook, this being supported by a suitable wire which may be of nickel or other suitable material. This construction is found to be peculiarly adapted for large amperage.

In Fig. 10, a modification is shown in which two filaments are mounted independently, the hooked ends of the filaments passing through independent helical coils, the filaments being connected in series through a V-shaped wire having coils at each end instead of having the hooks of two filaments pass through a single coil.

In Fig. 11, a construction is shown in which the hooked ends of the filaments are supported upon wires spreading the ends of the filaments apart a greater distance than the opening through which they are inserted into the globe. This is accomplished in essentially the same manner as described with reference to the looped filaments in connection with Fig. 5.

Heretofore it has generally been customary to mount the filaments of tungsten lamps practically parallel with the central arbor, such construction being convenient and more or less necessary when the filaments are rigidly fused to their supports. The general flexibility afforded by the mechanical connection, in accordance with my invention, facilitates the varied forms which are shown in the several figures and which are typical of the results that may be secured by this method of construction. It will also be understood that instead of employing hairpin shaped filaments, filaments which are straight and have hooks upon each end can be mounted in various forms, securing any one of a variety of positions within the globe. It is also practicable with this construction to insert filaments of either the hairpin shape or straight form into the globe

through the small hole at the top, thus repairing lamps in which one or more filaments may have become broken.

In practice I find that a mechanical contact of the ends of the filaments with the leading-in and supporting wires in many cases affords a sufficiently good electrical connection, particularly when a slight stress is exerted upon them by a suitable spring.

By employing tungsten rings and hooks for making direct contact with the tungsten filaments, the hot current carrying tungsten filament does not come into contact with metal other than tungsten, thereby avoiding liability of overheating metals of relatively lower melting point. The tungsten ring or hook may, if desired, be directly fused to the leading-in or supporting wire.

In Fig. 11^a, a modification is shown in which the wire is made V-shape so that while affording a loose connection it nevertheless tends to grip the filament slightly, thus holding the filament in contact with the supporting wire. In this construction the end of the filament has a species of pivotal contact connection permitting considerable freedom of movement in certain directions while a good electrical contact is insured. This form of construction is useful where the lamp is liable to be subjected to considerable shock or vibration.

I claim as my invention:

1. The method of constructing incandescent electric lamps, which consists in mounting the filaments loosely upon their supporting wires, placing the filaments parallel with the supporting arbor, bending the supports together, inserting the structure within the globe, and thereafter bending outward the supporting wires and spreading the filaments.

2. In an incandescent electric lamp, a filament having hooked ends, supporting wires for the filament, and helical coils carried by the supporting wires and engaging the hooked ends of the filament.

3. An incandescent lamp comprising a filament having hooked ends, supporting wires for the filament, and helical coils loosely carried by the supporting wires and engaging the hooked ends of the filament.

4. An incandescent lamp comprising a filament, supporting wires therefor, and helical coils loosely carried by the supporting wires and loosely surrounding but engaging the ends of the filament.

5. An incandescent lamp comprising a plurality of reversely bent filaments, the legs of different filaments crossing but not engaging each other.

6. An incandescent lamp comprising a plurality of reversely bent filaments, the legs of different filaments crossing but not engaging each other, and the legs of certain

of them being spread farther apart than those of others.

7. An incandescent lamp comprising a zig-zag filament, certain of the straight portions of which cross but do not engage each other.

Signed at New York, in the county of

New York, and State of New York, this
10th day of December A. D. 1908.

CHARLES F. SCOTT.
